UNITED STATES PATENT OFFICE.

MARQUIS L. GORHAM, OF ROCKFORD, ILLINOIS.

IMPROVEMENT IN CULTIVATORS.

Specification forming part of Letters Patent No. **131,818**, dated October 1, 1872.

To all whom it may concern:

Be it known that I, MARQUIS L. GORHAM, of Rockford, in the county of Winnebago and State of Illinois, have invented certain Improvements in Cultivators, of which the following is a specification:

My invention relates to that class of cultivator-teeth known as a friction or slip tooth, and is of such construction as will permit the tooth to be adjusted at a proper working-angle, and hold it sufficiently rigid to insure a thorough cultivation of the soil, and in the case of meeting with any unyielding obstruction will permit the tooth to yield so as to pass over such obstruction and save the parts from being injured or broken; and it further relates to the combination of the tooth and friction device with the drag-bars of cultivators or other agricultural implements.

Figure 1 is a side elevation embodying my invention. Fig. 2 is a plan view. Fig. 3 is a vertical transverse section cut through on dotted lines A.

B is a friction-plate, and is provided with a circular flange, C, which extends around its upper and front portion, and rises above the plane of the plate sufficient to secure the upper portions of the tooth D. The lower and rear portion of the plate B is provided with a circular slot, E, of suitable width and length. The circular flange C and circular slot E have a common center. D is a cultivator-tooth of ordinary construction, and is pierced to receive bolt F at such a distance from its upper end

that when the bolt F is passed through the slot E and tooth D the upper end of tooth D will rest against or near the flange C. F is a screw-bolt of suitable construction which passes through slot E and tooth D, by means of which tooth D may be adjusted to any suitable working-angle and held in such a manner as to insure a thorough cultivation of the soil, and in case of the tooth coming in contact with any unyielding obstruction will permit the tooth to yield until the obstruction is passed, when it can be readjusted by means of screw-bolt F. The forward portion of friction-plate B is provided with an extension piece, G, which is provided with suitable flanges H to receive beam K. K is a beam slotted to receive piece G of friction-plate B, to which it is secured by bolt or pin L, as shown. In this instance the friction-plate B is of uniform thickness, which will hold the tooth with a uniform tension in its rearward movement on plate B; but if it is desired to give greater freedom to the backward movement of the tooth on plate B the slotted portion thereof may be tapered rearward.

I claim as my invention—

The single friction-plate B, constructed as described, in combination with standard D, clamp-bolt F, and beam K, as and for the purpose set forth.

MARQUIS L. GORHAM.
